LIONEL M. WOOLSON, DECEASED, LATE OF DETROIT, MICHIGAN, BY EMMA F. WOOLSON, EXECUTRIX, OF BLOOMFIELD VILLAGE, MICHIGAN, ASSIGNOR TO PACKARD MOTOR CAR COMPANY, OF DETROIT, MICHIGAN, A CORPORATION OF MICHIGAN

INTERNAL COMBUSTION ENGINE

Application filed July 21, 1930. Serial No. 469,325.

This invention relates to internal combustion engines and more particularly to engines of the Diesel or compression-ignition type.

With one type of compression-ignition engine, it is the usual practice to cause liquid fuel injections into compressed air charges in the cylinders by means of pressure devices actuating in accordance with the crank shaft speed, and consequently the degree of pressure under which the fuel is injected into the combustion chambers varies in accordance with the engine speed. One of the prime requisites for the continued operation of a compression-ignition engine requires that the liquid fuel be properly atomized and sufficiently projected far enough into the compressed air charges such that there will be a uniform mixture of the fuel with the oxygen, and with high speed engines the time in which such results must be attained is a very small fraction of a second. With the type of fuel device above mentioned, it is difficult to maintain combustion when the engine is idling, and it is more difficult to start the engine because the pressure developed behind the liquid fuel under such circumstances is not sufficient to give either the desired penetration of the air charges by the fuel or the desired atomization thereof.

An object of the invention is to provide an internal combustion engine of the compression-ignition type with actuating mechanism for the fuel injection devices which will cause substantially as high a pressure to be developed behind the injected liquid fuel charges during idling or starting as when the engine is running under load.

Another object of the invention is to assure the proper atomization and pressure behind liquid fuel charges which are injected into compressed air charges in the combustion spaces of an internal combustion engine by the use of a cam, running in accordance with the engine speed, which is effective during the higher speed range and by an auxiliary mechanism which is effective during the lower speed range to cause a faster pump plunger actuation than would result if the cam were effective.

A further object of the invention is to provide mechanism for actuating the plungers of fuel injection devices for compression-ignition engines which are effective to maintain a sufficient plunger injection impulse or movement to insure a pressure behind the fuel charges sufficient to penetrate compressed air charges and form a mixture therewith of a character which will be ignited by compression at any speed under which the crank shaft of the engine is turning.

Still another object of the invention is to provide a fuel injecting mechanism for compression-ignition engines in which a cam causes effective injection strokes during the high speed range of the engine and in which radially movable abutments associated with the cam cause a fast injection stroke of the devices when the engine is running in its slower speed range.

These and other objects of the invention will appear from the following description taken in connection with the drawings, which form a part of this specification, and in which:

Fig. 1 is a rear elevational view of a radial type of compression-ignition engine, partly broken away and partly in section to show the elements essential to an understanding of this invention;

Fig. 2 is a vertical sectional view of the engine taken on line 2-2 of Fig. 1;

Fig. 3 is a vertical sectional view of the mechanism for actuating the fuel injection devices taken on line 3-3 of Fig. 2;

Fig. 4 is a sectional view of the nozzle portion of one of the injection devices associated with a fragment of a cylinder;

Fig. 5 is a fragmentary plan view of the mechanism for actuating the plunger operating devices.

Referring to the drawings by characters of reference, 10 indicates the crank case of an internal combustion engine of the Diesel or compression-ignition type from which a plurality of cylinders 11 extend radially. The interior of the crank case is divided into two compartments by a diaphragm 12, and a removable cover plate 13 closes the open rear end of the crank case.

The cylinders are each preferably formed as a steel forging which includes a barrel and an integral dome 14 upon each of which domes is secured a head 15. In order to provide for air being drawn into and exhaust being expelled from the combustion chamber 16, which is between the pistons 17 and the domes 14, there is provided a Venturi passage 18 extending through each of the associated heads and domes. Such passages are arranged to extend at an angle to the axis of the cylinders and tangentially of the interior walls thereof so that air being drawn into the cylinders by the pistons will be given a rotary movement which will continue during the compression strokes of the pistons. In order to control flow through each of the Venturi passages, there is provided a valve 19 opened by suitable mechanism driven from the crank shaft and including a push rod 20 extending into the crank case; a plurality of springs 21 serve to normally maintain the valves in closed relation with the passage.

Liquid fuel oil, in atomized form and under a relatively high pressure, is injected into each of the cylinders during the air compression strokes by an individual injection device consisting of a nozzle portion and a pump portion. The nozzle portions of the several units are connected by a manifold which consists of conduits 22 which are connected at their ends with unions 23 secured upon each of the pump sections by the nuts 24. A reservoir and low pressure pump (not shown) are connected with the manifold for maintaining the same completely filled with fuel oil and an overflow return conduit 25 leads back to the reservoir from the uppermost of the unions 23.

Each nozzle includes a barrel 26 having the forward end 27 thereof extending through an aperture in the cylinder wall, and the pump and nozzle units are secured rigidly to the cylinders by bolts 28 which extend through flanges forming a part of the nozzle. A chamber extends axially through the major portion of the nozzle and arranged therein is a reciprocable valve element 29 which is provided with a conical head within the flared end of the nozzle chamber. Associated with the other end of each of the valve members is a stop member 30 which is adjustable to limit the movement of the associated valve so that the head thereof will never quite engage the nozzle barrel. A coil spring 31 is arranged to normally urge each valve into its position of nearest closure.

A pump casing 32 is screwed upon a depending neck portion of the nozzle barrel, and arranged within the pump casing is a barrel 33 within which the plunger 34 is reciprocated. There is a passage 35 establishing communication between the bore of the barrel and the chamber in the nozzle, such

passage having therein a one-way valve 36 which prevents leakage of fuel oil and air from the nozzle into the pump barrel. The pump barrel and casing are provided with a plurality of registering ports 37 which are arranged to open into the unions 23 so that when the plunger 34 uncovers such ports, oil will be moved into the nozzle and pump barrels to maintain the same full of oil, such communication being cut off when the plungers are moved past the ports upon their injection strokes.

A push rod is associated with each of the pump plungers and extends into the crank case, each of such push rods consisting of a guided section 38 and a section 39 pivotally associated with the inner end of the guided section. A spring 40 is arranged intermediate the pump casing and the pump barrel and serves to normally move the associated plunger into a position uncovering the ports 37. Each of the push rod sections 39 engages with the free end of a pivoted slipper, as indicated at 41, and such slippers are carried by shafts 42 which are supported by the partition 12 and the end cover 13. The free ends of the slippers are formed with an arcuate groove extending longitudinally thereof, and the inner end of the push rod sections 39 can be moved along such grooved surfaces in order to vary the stroke of the plungers beyond the ports 37. In order to simultaneously adjust all of the push rods, there is provided a ring 43 which is carried by the partition wall 12 and upon which are pivoted the links 44 which in turn are each pivoted to one of the push rod sections 39. Rotation of the ring 43 will move the push rods longitudinally of the slippers in a similar manner, and the ring is provided with a rack 45 having a gear segment 46 associated therewith and rotated by a shaft 47 through means of a lever 48. Suitable link mechanism can be associated with the lever 48 for rotating the shaft to cause rotation of the ring 43 and a consequent adjustment of the plunger strokes beyond the ports 37. When the plungers close the ports 37, the injection of the fuel charges will commence and the length of such stroke after closing the ports 37 will determine the quantity of the fuel charges displaced from the nozzles into the compressed air charges in the cylinders.

The fuel injection devices described are preferably actuated by mechanism driven from the crank shaft 49 which extends axially through the partition wall 12. A cam 50 is keyed upon the rear end of the crank shaft and is provided with an extended hub portion 51 upon which a cam 52 is rotatably mounted. Fixed to the rear end of the crank shaft is a gear 53 which meshes with a gear 54 carried upon a shaft 55, and upon such shaft is fixed another gear 56 which meshes with a gear 57 formed on the inner wall of the

periphery 58 of the cam 52. Such gearing is of a reduction type and preferably of a character such that the cam 52 is driven at one-eighth the crank shaft speed and in an opposite direction therefrom. Looking at the rear end of the engine, the crank shaft and cam 51 will rotate in a clockwise direction while the cam 52 will rotate in an anti-clockwise direction. The periphery of the cam 52 is formed with four lobes 59 which are similar in form and equally spaced, such lobes being arranged in the same vertical plane with the slippers 41. The cam 52 is also provided on its periphery with a plurality of lobes 60 which are arranged in a vertical plane to actuate slippers 61 which are pivotally mounted on the shafts 52 and with which the valve push rods 20 are associated, such lobes being arranged to cause the slippers 61 to move in, a direction to cause an opening movement of the valves during the suction and exhaust strokes of the pistons. The lobes 59 are preferably arranged so that there will be one fuel injection stroke from each device, caused by their contact with the slippers 41, upon every two revolutions of the crank shaft.

When the engine is running in its higher speed range, the rotation of the cam 52 is fast enough to cause an injection movement of the fuel plungers 34 to deliver sufficient pressure behind the fuel charges injected into the cylinders to insure that they will penetrate substantially to the axis of the compressed air rotating in the cylinders, and thus one revolution of the compressed air will cause a uniform distribution therein of the atomized liquid fuel charge being injected so that a homogeneous mixture results and, consequently, will readily ignite through heat of compression. When the engine is running or being cranked in its lower range of speed, the cam is rotating at one-eighth such speed and will not impart a sufficient speed of movement to the pump plungers when the lobes 59 contact with the slippers 41 to exert a pressure sufficient to cause a pressure behind the fuel resulting in any substantial penetration thereby of the compressed rotating air. This lack of penetration caused by decreased pressure will not produce the proper distribution of the fuel in the air to result in a mixture which will sustain combustion through the heat of compression, and as a result, starting of an engine of this character is extremely difficult and stalling of the engine through lack of ignition of the charges is a common occurrence when idling.

In order to maintain pressure behind the fuel injected into the combustion chambers when the engine is running or being cranked in its lower range of speed, there is provided auxiliary actuating mechanisms which are associated with the cam 52 and actuated by the cam 50 fixed to the crank shaft. A movable radially extending abutment 62 is pilot-

ed in the periphery of the cam 52 and includes a flange portion 63 which acts as a stop with the inner face of the cam periphery to limit the movement of the abutment beyond the outer face of the cam periphery. The radial abutments extend through apertures in flanges 64 projecting laterally from the cam 52 and a coil spring 65 surrounds each abutment and engages the flanges 63 and 64, such spring normally exerting a pressure against the abutment to project beyond the periphery of the cam. A rock lever 66 is pivoted at one end to the inner end of each of the radial abutments and is also pivoted by means of pins 67 to the web portion of the cam adjacent the cam 50. The periphery of the cam 50 is provided with an abrupt face 68 and the free end of each of the rock levers 66 is provided with a toe portion 69 which is arranged to ride upon the periphery of the cam 50. When the abrupt face of the cam periphery passes beneath the toe of the rock levers, the spring 65 which has been compressed will be suddenly released and will cause the abutments 62 to be projected outwardly beyond the periphery of the cam 52. It is to be observed that each of the actuating faces of the abutments 62 is formed to lie flush with the operative face of the cam lobes 59 when in the innermost position of their movement.

When the engine is operated in its higher speed range, the lobes 59 of the cam 52 will be effective to cause actuation of the slippers and the fuel injection plungers, but when the engine is running in its lower speed range, the abutments 62 will be effective to actuate the slippers 41 and the fuel plungers. When the engine is running in its higher speed range, the abutments are ineffective because of the lag of the springs 65, the movement of the abutments after the abrupt face of the cam passes under the rock levers 66 and the consequent release of the springs 65 will not cause the abutments to move fast enough to come into effect prior to the time at which the actuating face lobes 59 will have rocked and passed under the slippers 41. When the engine is running in its slower range of speed, the rotation of the cam 52 is so slow that the abutments will move into effective position to actuate the slippers 41 prior to the time the lobes 59 become effective. This effective position of the radial abutments will cause a sudden impulse movement to be given to the slippers as they pass thereunder, such imparted movement being much faster than the movement which would be given by the cam 52 under such speed conditions, and consequently the speed of the movement of the plungers 34 in their injection strokes will be increased likewise. This fast movement of the pump plungers during the engine slow speed range will cause a higher pressure to be developed behind the

fuel charges injected into the cylinders and, consequently, when the engine is idling or being cranked, this higher pressure is sufficient to cause the fuel charges to be atomized and 5 to penetrate the rotating compressed air charges to an extent which will cause a fuel mixture of a character which will readily ignite through compression by the pistons. It will be seen that the cam 50 is rotating at 10 crank shaft speed and is associated with the lobes of the cam 52 so that the abutments will be actuated in a timed relation to be effective as the cam lobes approach the slippers 41.

With the mechanism described for actuating the fuel injection devices, it is possible to maintain a minimum pressure upon the fuel charges injected into the compressed air in the cylinders which is sufficient to cause a distribution of the fuel in an atomized condition such that the resulting mixture will readily ignite upon compression by the pistons, irrespective of the speed at which the engine is running or being cranked, and the danger of the engine stalling when using fuel 20 injection mechanism of the engine driven plunger type is eliminated and starting conditions are materially improved.

While there is herein described in some detail a specific embodiment of the invention, 30 which is deemed to be new and advantageous and may be specifically claimed, it is not desired that it be understood that the invention is limited to the exact details of the construction, as it will be apparent that changes may 35 be made therein without departing from the spirit or scope of the invention.

What is claimed is:

1. In an internal combustion engine, a 40 pressure device including a plunger for injecting atomized liquid fuel into compressed air charges in a combustion space, an engine driven cam for causing injection strokes of the plunger above a predetermined engine speed, and radially reciprocable abutments carried by the cam for effecting plunger injection strokes below the predetermined engine speed.

2. In an internal combustion engine, a 50 pressure device including a plunger for injecting atomized liquid fuel into compressed air charges in a combustion space, an engine rotated cam for causing injection strokes of the plunger while the engine is running above a predetermined speed, radially reciprocable abutments carried by the cam for effecting plunger injection strokes below the predetermined engine speed, and spring means for actuating the abutments to place them in effective position.

60 3. In an internal combustion engine, a pressure device including a plunger for injecting atomized liquid fuel into compressed air charges in a combustion space, an engine driven cam having a plurality of lobes extending from a base circle, said lobes effecting

actuation of the plunger in injection strokes while the engine is running above a predetermined speed, and radially reciprocable means extending through the faces of the cams for effecting actuation of the plunger while the engine is running below the predetermined speed.

4. In an internal combustion engine, a pressure device for injecting atomized liquid fuel into compressed air charges in a combustion space including a plunger, an engine driven cam having a plurality of lobes extending from a base circle, said lobes effecting actuation of the plunger in injection strokes while the engine is running above a predetermined speed, and axially reciprocated means extending radially through the faces of the cams for effecting actuation of the plunger while the engine is running below the predetermined speed.

5. In an internal combustion engine, a crank shaft, a cam rotated at reduced speed from the crank shaft, a liquid fuel injection device including a plunger, a rock lever pivoted in relation to be actuated by the cam, a rod structure intermediate the plunger and the forward end of the rock lever, spring means urging the plunger and rod structure toward the rock lever, and radially movable abutments reciprocable through the periphery of the cam, said abutments being arranged to engage the rock lever and cause injection strokes of the plunger in the slow speed range of the cam rotation and ineffective during the high speed range of the cam.

6. In an internal combustion engine, a pressure device for injecting atomized liquid fuel into compressed air charges in a combustion space including a plunger, an engine driven cam for causing injection strokes of the plunger above a predetermined engine speed, radially reciprocable abutments carried by the cam for effecting plunger injection strokes below the predetermined engine speed, and means imparting a fast movement to the abutments in their movement causing plunger injection strokes.

7. In an internal combustion engine, a pressure device for injecting atomized liquid fuel into compressed air charges in a combustion space including a plunger, an engine driven cam for causing injection strokes of the plunger above a predetermined engine speed, radially reciprocable abutments carried by the cam for effecting plunger injection strokes below the predetermined engine speed, and pressure means imparting a fast movement to the abutments in their movement causing plunger injection strokes.

8. In an internal combustion engine, a pressure device for injecting atomized liquid fuel into compressed air charges in a combustion space including a plunger, a cam driven at a reduced speed by the engine for causing injection strokes of the plunger above a pre-

70

determined engine speed, radially reciproca-
ble abutments carried by the cam for effecting
plunger injection strokes below the said pre-
determined engine speed, and a cam cooper-
5 ating with the abutments to effect their
actuation.

9. In an internal combustion engine, a pres-
sure device for injecting atomized liquid fuel
10 into compressed air charges in a combustion
space including a plunger, a plural lobe cam
rotated at a reduced speed from a moving
engine part, abutments carried by the cam
and adapted to be reciprocated through the
15 face of the lobes, a rock lever pivoted adjacent
the cam, spring pressed connecting means
intermediate the plunger and the rock lever,
and springs normally urging the abutments
beyond the cam lobes, said cam being effective
20 to actuate the rock lever to cause plunger in-
jection strokes above a predetermined engine
speed, said abutments being effective to actu-
ate the rock lever to cause plunger injection
strokes below the predetermined engine
speed.

25 10. In an internal combustion engine, a
pressure device for injecting atomized liquid
fuel into compressed air charges in a combus-
tion space including a plunger, a multi-lobe
30 cam rotated at a reduced speed from a mov-
ing part of the engine, abutments carried by
the cam and piloted in the periphery thereof,
said abutments being reciprocably associated
35 with the cam through the face of the lobes,
a rock lever pivoted adjacent the cam in a
relation to be actuated by the lobes and the
abutments, spring means pressing the abut-
40 ments beyond the cam lobe faces, a connection
between the rock lever and the plunger, and
means for compressing and releasing the
spring to give impulsive movements to the
abutments.

45 11. In an internal combustion engine, a
pressure device for injecting atomized liquid
fuel into compressed air charges in a combus-
tion space including a plunger, a multi-lobe
cam rotated at a reduced speed from a mov-
50 ing part of the engine, flanged abutments car-
ried by the cam and piloted in the periphery
thereof, brackets extending from the cam
through which the abutments extend, coil
55 springs surrounding the abutments and seat-
ed against flanges thereof and the brackets, a
rock lever pivoted adjacent the periphery of
the cam, connections between the free end of
the rock lever and the plunger, and cam
60 means for moving the abutments inwardly of
the multi-lobe cam and compressing the
spring, said spring imparting a fast outward
movement to the abutments for actuating the
rock lever after the cam means passes there-
under with the engine in the slow speed range,
the spring return being too late for the abut-
ments to actuate the rock levers when the
65 engine is running faster than the slow speed
range.

12. In an internal combustion engine, a
pressure device including a plunger for in-
jecting atomized liquid fuel into compressed
air charges in a combustion space, an engine
70 driven cam having four similar spaced lobes
projecting from the base circle thereof for
causing injection strokes of the plunger above
a predetermined speed, a crank shaft, a driv-
ing connection between the crank shaft and
75 the cam adapted to rotate the cam in a reverse
direction to that of the crank shaft and at
one-eighth its speed, a reciprocable abutment
carried by the cam and extending radially
thereof through each lobe and adapted to pro-
ject through the effective face thereof, a cam
80 fixed to the crank shaft having a single lobe
thereon, a rock lever associated with each
abutment and adapted to be actuated by the
single lobe cam for moving the abutment in-
wardly of the cam, and a spring associated
85 with each abutment adapted to be compressed
by the inward movement of the abutment and
to be suddenly released prior to the lobe of the
fixed cam passing beneath the lever to project
90 the abutments beyond the cam lobes to en-
gage with the plunger actuating mechanism
when the engine is running in a slow speed
range, the lobes on the cam being effective to
operate the plunger actuating mechanism
95 when the engine is in its higher speed range.

13. In an internal combustion engine, a
pressure device for injecting atomized liquid
fuel into compressed air charges in a combus-
tion space including a plunger, an engine ro-
100 tated cam for causing injection strokes of the
plunger, said cam having a plurality of lobes
extending from the base circle, a reciprocable
abutment extending through the effective face
105 of each lobe, said abutments having a face
conforming in outline to the surrounding
abutment faces when in their innermost pos-
ition, and means for projecting the abutments
110 beyond the lobes to cause plunger injection
strokes when the engine is running below a
predetermined speed.

14. In an internal combustion engine, a
pressure device for injecting atomized liquid
fuel into compressed air charges in a com-
bustion space including a plunger, a rotat-
115 ably mounted multi-lobe cam for causing in-
jection strokes of the plunger, a crank shaft,
reduction gearing for rotating the cam from
the crank shaft and in a reverse direction rel-
ative thereto, an abutment piloted through
120 each cam lobe, spring means normally pro-
jecting each abutment beyond the associated
cam lobe, and a single lobe cam fixed to
the crank shaft causing compression and sud-
den release of the springs.

15. In an internal combustion engine, a
pressure device for injecting atomized liquid
fuel into compressed air charges in a com-
bustion space including a plunger, a rock
lever, connections between a free end of the
125 rock lever and the plunger, a spring pressing
130

- the plunger and connections toward the rock lever, a cam having peripheral lobes, a crank shaft, reduction gearing between the crank shaft and cam, said gearing rotating the cam in the opposite direction from that in which the crank shaft rotates, a radial abutment extending through each cam lobe and adapted to be projected therefrom to actuate the rock lever and cause plunger injection strokes 5
- 10 while the engine is running below a predetermined speed, said cam actuating the rock lever while the engine is running above the predetermined speed, a pivoted lever connected to the inner end of each abutment, a 15 spring associated with each abutment and exerting pressure to project the same beyond the cam lobes, and a single lobe cam fixed to the crank shaft and coacting with the pivoted levers to move the abutments inwardly of the 20 lobes during the major portion of its rotation and to suddenly release the same in a timed manner to cause effective actuation of the rock levers below the predetermined engine speed.
- 25 16. In an internal combustion engine having cylinders extending radially from the crank case, pressure devices including a plunger for injecting atomized liquid fuel into compressed air charges in the cylinders, 30 one of said devices being fixed to each cylinder, a plurality of rock levers circularly arranged and pivotally mounted within the crank case, a connecting rod structure between each plunger and rock lever, a four 35 lobe cam positioned to rotate in a relation to actuate the rock levers, said lobes actuating the rock levers to impart injection strokes to the plungers when the engine is running above a predetermined speed, radial abutments carried by the cam and adapted to be reciprocated through the effective faces of the lobes, and means for imparting sudden movement to the abutments to project them beyond the lobe faces to actuate the rock 40 levers when the engine is running below the predetermined speed.
- 45 17. In an internal combustion engine, a pressure device including a plunger for injecting atomized liquid fuel into compressed air charges in a combustion space, an engine 50 rotated cam having four equally spaced similar lobes extending from the base circle, a rock lever pivotally associated to be actuated by the lobes of the cam, connecting means between the free end of the rock lever and the plunger, a crank shaft, reduction gearing driving the cam from the crank shaft at a reduced speed, abutments extending radially of and carried by the cam, one of said abutments extending through the operative face of each cam lobe, levers pivoted to the cam and associated to cause axial movement of the abutments, a spring associated with each abutment normally urging projection there- 55 of beyond the lobes, and a cam driven by the 60
- 65

crank shaft and coacting with the pivoted levers for moving the abutments inwardly of the cam lobes against the tension of the associated springs and suddenly releasing the same, said cam being arranged to actuate and release the abutments in a timed relation such that they will be effective to actuate the rock levers upon the approach of the actuating faces of the cam lobes when the engine is running below a predetermined speed, the speed of the cam above the predetermined engine speed being adequate to cause actuation of the rock levers by the lobes prior to the projection of the abutments into effective position. 70

18. In an internal combustion engine, a pressure device including a plunger for injecting atomized liquid fuel into compressed air charges in a combustion space, an engine rotated cam for causing injection strokes of the plunger, said cam having a plurality of lobes extending from the base circle thereof, radially reciprocable abutments extending one through the face of each lobe, means for reciprocating said abutments in a timed relation to effect fuel injections, and means on the abutments for limiting the outward projection thereof. 80

In testimony whereof, I have hereunto subscribed my name this 17th day of July, 95 1930.
